(57) **CLAIM**

The ornamental design for a sign holder, as shown and described.

DESCRIPTION

This application is related to U.S. application Ser. No. 13/364, 914 filed on an even date herewith, and entitled “Media Display Assembly and Merchandising System Associated Therewith.”

FIG. 1 is a front, perspective view of a sign holder showing a first embodiment of our new design;

FIG. 2 is a front view thereof;

FIG. 3 is a rear view thereof;

FIG. 4 is a rear view thereof with environmental subject matter removed to more clearly illustrate the claimed design;

FIG. 5 is a left side view thereof;

FIG. 6 is a right side view thereof;

FIG. 7 is a top view thereof;

FIG. 8 is a bottom view thereof;

FIG. 9 is a bottom view thereof with environmental subject matter removed to more clearly illustrate the claimed design; and,

FIG. 10 is a front, perspective view thereof illustrated with additional environmental subject matter.

The features shown in broken lines depict environmental subject matter only and form no part of the claimed design.

1 Claim, 6 Drawing Sheets
